STABILIZER FOR AEROPLANES

Application filed May 19, 1928. Serial No. 278,952.

This invention relates to stabilizers for aircraft in general, and the object of the invention, broadly stated, is to provide means whereby the lateral and longitudinal stability of the craft is maintained without any attention on the part of the operator of the machine.

Another object in view is to provide means for stabilizing aircraft, which means is adapted to operate either automatically or be under the control of the aviator as may be required.

Another object in view is to provide simple and effective means for throwing the stabilizing apparatus into and out of operation automatically so that the aviator may have absolute control of the stability of the machine at any time it may be found necessary.

With the above and other objects in view, the invention consists in the novel construction, combination and arrangement herein fully described, illustrated and claimed.

In the accompanying drawings:—

Figure 1 is a side elevation of an aeroplane showing the improved stabilizing apparatus in its applied relation thereto.

Figure 2 is an enlarged fragmentary vertical longitudinal section showing the connection of the lateral stabilizing device with the engine shaft.

Figure 3 is a vertical transverse fragmentary section showing the clutch mechanism for controlling the stabilizing apparatus.

Figure 4 is a fragmentary bottom plan view of the same.

Figure 5 is a fragmentary vertical section taken at a right angle to Figure 3.

Figure 6 is a rear elevation of one of the stabilizing vanes.

Figure 7 is an elevation of plan thereof taken at a right angle to Figure 6.

Figure 8 is a plan view of the complete machine equipped with the stabilizing apparatus.

Figure 9 is a fragmentary plan view on an enlarged scale showing the fore and aft stabilizing clutch means.

Figure 10 is a fragmentary vertical longitudinal section of the same.

Referring to the drawings 1 designates the

fuselage of an aeroplane, 2 and 3 the upper and lower supporting surfaces thereof, 4 the ordinary propeller, 5 a landing gear, 6 the vertical rudder and 7 the horizontal rudder. The ailerons are located at 8 and are shown as associated with the outer rear corners of the top or upper supporting surface 2.

The means for automatically maintaining the lateral equilibrium or stability of the craft, comprises a stabilizing vane 9 which is located directly over the longitudinal center of the fuselage and in the vertical plane of the longitudinal axis thereof and the engine shaft and propeller shaft. The stabilizing vane 9 is fixedly attached to the rearwardly extending arm 10 of a laterally swinging frame comprising a forwardly and downwardly curved portion 11 which is connected,

in the preferred embodiment of this invention, to a loose collar or sleeve 12 surrounding the engine shaft as shown in Figure 2, the connection between the member 11 and the collar 12 being shown in the form of links or rings 13 passing through each other and thus allowing the frame carrying the stabilizing plane 9 to swing laterally on the longitudinal axis of the fuselage. Connected fixedly to the arm 10 is a substantially and normally upright standard or post 13' which is fixedly secured at its lower end to a longitudinally extending rock shaft 14 mounted in bearings in spaced parallel frame members 15 within the fuselage. Fast on the shaft 14

is a collar 16 having a notch or slot 17 therein, and arranged slidably on the rock shaft 14. Another collar 18 having a projection 19 movable into and out of the slot 17 of the collar 16, whereby the collar 18 may be caused to rotate with or be left free from the shaft 14. Fixedly connected to the collar 18 is a horn or lever arm 20 to which are attached the ailerons' operating connection 21 which extend to the ailerons or lateral balancing or stabilizing surfaces 8. The collar 18 is shifted by means of a link 22 connected to one arm of a lever 23 pivotally mounted on the frame of the fuselage, said lever being operated by another rod or connection 24 which extends to a hand lever 25. By the means just described, provision is made for

the automatic control of the lateral stability of the machine or manual control of the same.

In the preferred embodiment of the invention as it relates to the stabilizing vane 9, said vane consists of two rearwardly diverging planes or surfaces 26 mounted upon and connected to a suitable frame work 28 which is fixedly secured to the rearwardly extending arm 10 of the laterally swinging frame above referred to. By providing said vane with rearwardly diverging surfaces, the proper action of the stream of air thereon during the flight of the machine is insured and the lateral stability of the machine is correspondingly insured.

The means for automatically controlling the fore and aft stability of the machine, comprises another stabilizing vane 29 corresponding in all particulars with the vane 9 hereinabove described but disposed at a right angle thereto as shown in Figure 8. The vane 29 is mounted fixedly on the rear extremity of a normally horizontal arm 30 adapted to move upwardly and downwardly in a normally vertical plane. At its inner end the arm 30 is journaled upon a rock shaft 31 extending transversely of the fuselage and projecting from one side thereof, the inner end of the arm 30 having a notch 31' thereon which is adapted to be engaged and disengaged by a projection 32 on a slidable collar or sleeve 34 on the shaft 31, said collar or sleeve being connected to the shaft 31 by means of a key or feather 35. From the lever 23 an operating rod 24' extends to one arm of a bell crank lever 38 pivotally mounted on the frame of the machine.

The other arm of the elbow lever 38 has connected thereto a rod 39 which has a jointed connection with the shiftable collar 34 for the purpose of shifting the latter into and out of engagement with the adjacent end of the vane carrying arm 30 as best illustrated in Figure 9. Fast on the shaft 31 are one or more posts or horns 40 from which the controlling connections 41 lead to the elevator or horizontal rudder of the machine. When the clutch mechanism shown in Figure 9 is in clutch position, it will now be observed that as the machine tilts on its transverse axis or departs from a true fore and aft horizontal line of flight, the stream of air acting on the vane 29 serves to rock the shaft 31 and through the connections described, the elevator or horizontal rudder is correspondingly changed as to its angle for the purpose of restoring the craft to an even keel.

The operation of the vane 9 is the same as that just described in connection with the vane 29. As the machine loses its lateral balance, for example when the right hand side of the machine becomes depressed, the vane 9 is held in its normal position swinging over to the left hand side of the longitudinal center of the fuselage, thereupon working the

control which operates the ailerons, moving one of the ailerons or laterally balancing surfaces downwardly at its trailing edge and corresponding elevating and trailing edge of the other aileron or supporting surface. When the stabilizer controlling clutches are in their clutched positions, the lateral and fore and aft stability of the machine are automatically provided for. When however, the aviator or operator of the machine desires to have complete control of the fore and aft and lateral stabilizing surfaces, he unclutches the parts and thereby throws the stabilizing vane out of operation.

While we have shown and described the stabilizing apparatus applied to an aeroplane of the biplane structure, or type, it will of course, be obvious that the stabilizing apparatus is applicable to monoplanes, biplanes and various other types of aircraft as said stabilizing apparatus will operate in connection with any aircraft while proceeding at a comparatively rapid pace in actual flight through the air.

Having described our invention, we claim:

1. In an aeroplane having stabilizing ailerons thereon for maintaining the same in transverse balance, of automatic stabilizing means comprising an aileron control vane, vertically extended supporting means therefor pivotally supported upon bearings disposed in axial alignment with the longitudinal axis of the machine and connections from said supporting means to the ailerons, said connections including a releasable clutch device and manual means for actuating the clutch device for connecting or disconnecting the control vane for automatic or manual control of the ailerons as desired.

2. In combination with the ailerons located on the plane of the aeroplane, automatic stabilizing means above the fuselage of the aeroplane, a rock shaft journalled longitudinally of the fuselage, a member rigidly connecting said rock shaft with said frame, a clutch element fixed on said rock shaft, a sleeve slidable and rotatable upon said shaft and formed with an arm, flexible members connecting said arm with the ailerons, a lever carried by said sleeve and engageable with said clutch element whereby to lock said sleeve for rotation with said rock shaft, and manually controlled means for shifting said lever.

3. In combination with the ailerons located on the planes of the aeroplane, stabilizing means comprising a laterally tilttable frame extending longitudinally above the fuselage of the aeroplane, a collar loosely surrounding the engine shaft of the aeroplane, a loose connection between said collar and the forward end of said frame, a rock shaft journalled longitudinally of the fuselage, an upright rigidly secured to said rock shaft and to

said frame, a collar rigidly secured to said rock shaft and formed with a notch, a slide-
5 able collar on said shaft rotatable with re-
spect thereto and formed with an upstanding
arm, flexible members connected with said
arm and with the ailerons, an elongated lever
carried by said slideable collar and having one
10 end adapted to be engaged beneath said
notch whereby to lock said sleeve for ro-
tation with the rock shaft, and a manually con-
trolled lever for moving said first named
lever.
